UNITED STATES PATENT OFFICE.

GUSTAVUS A. KARWIESE, OF NEW YORK, N. Y.

LOCOMOTIVE-BOILER.

SPECIFICATION forming part of Letters Patent No. 398,161, dated February 19, 1889.

Application filed March 30, 1887. Serial No. 233,079. (No model.)

To all whom it may concern:

Be it known that I, GUSTAVUS A. KARWIESE, of New York, in the county of New York and State of New York, have invented certain new and useful Improvements in Locomotive-Boilers; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in locomotive-boilers, and has for its object to economize fuel to the greatest extent and to develop a maximum power with a minimum expenditure.

My invention consists in the enlargement of the fire-box in such manner as to utilize all the available space permitted by the position of the tracks, so that, instead of making the fire-box as deep as usual, I make it wide, extending out between the drivers, so that I can readily stoke the fire throughout all its grate area, and thus insure perfect combustion and give time for the consumption of the gases, which in the deep elongated boxes heretofore could not be successfully done.

Another beneficial result of the arrangement of my fire-box is that it is near the ground, avoiding the serious objection heretofore existing of being "top-heavy," which also in a large measure prevents "swinging," and my invention further consists in certain novel features of construction and combinations of parts, more fully described herein-after, and particularly pointed out in the claims.

In the drawings hereto annexed, Figure 1 is a central vertical longitudinal section of my improved engine frame, boiler, and tender. Fig. 2 is a central horizontal section taken on a line through the fire-box above the grate and frame and partly a top plan view of the frame and tender-engine tanks; and Fig. 3 is a detail sectional view on line *a b*, Fig. 1, of one of the brace-rods extending through the fire-box and the water-tube surrounding the same.

A is the boiler, provided with fire-tubes of

the usual make, the barrel of which may be varied in diameter as desired.

B is the fire-box, of about the usual depth, but extending transversely between and beyond the driving-wheels as far as the position of the tracks will permit, by which I obtain a very much increased area of grate-surface, and which, by its position and contour, is readily accessible for stoking, and at the same time increasing largely the steam-generating surface, the barrel of the boiler and the fire-box portion presenting in horizontal section substantially the form of a T.

At the smoke-box end of the boiler an extension, J, is formed around the uptake, which is constructed with a downwardly-inclined bottom forming a deflecting-plate, *d*, which deflects the sparks and cinders into the bottom of the smoke-box, from which they can be blown out in a suitable manner. This extension J, as will be seen by reference to the drawings, forms a portion of the boiler and steam-generating surface, thereby utilizing all the heating-surface possible. It will be observed that the inclined bottom of the extension J of the smoke-box also forms a sediment-chamber, from which the sediment is blown through a mud-plug, *i*.

In the construction shown the traction force of the tender is utilized by converting the same into an auxiliary engine, C, having operating mechanism independent of but operating simultaneously with the operating mechanism of the locomotive proper, both being supplied with steam from the same boiler. This auxiliary engine is provided with the water-tanks D, arranged in such manner as to form coal-repositories between them.

On the engine-boiler I locate a steam-dome, E, immediately over the fire-box, and said dome contains the steam dry-pipe F, connected with a chamber, G, from which two steam-supply pipes, H I, extend to the respective engines.

As shown in the drawings, the boiler and other parts of the locomotive are supported by skeleton frames—preferably three in number and suitably jointed together. The frame is made to conform to the shape of the fire-box and extend beneath it, but the angle is not so abrupt as to endanger the fracturing of

- the said frame; but in order to fully strengthen this portion of the frame the stay-rods *e f* are secured to the same and run directly through the fire-box. These rods are prevented from 5 injury by heat by the inclosing water-tubes *e'*, communicating with the boiler and surrounding said rods and extending through the fire-box. The lower portion of the fire-box is surrounded by water, as shown.
- 10 The boiler is set on the frame in such manner as to be entirely free from the action of the engine-frame; therefore the danger of springing the joints or boiler-seams is overcome.
- 15 The engine is provided with the usual appliances for its operation, the same throttle answering for both engines, and the steam is therefore let into both simultaneously.
- It is clearly evident that various slight 20 changes might be made in the form and arrangement of the parts described without departing from the spirit and scope of my invention.
- What I claim is—
- 25 1. The combination, in a locomotive-boiler, of the fire-box, the smoke-box connected by flues with the fire-box, and a top extension over the smoke-box, forming a part of the boiler and having a downwardly-inclined bottom forming a deflecting-plate at the top of 30 the smoke-box, substantially as described.

2. The combination, with a locomotive-boiler, of an extension over the smoke-box forming a part of the boiler, the bottom of said extension forming a deflector for the 35 sparks, an upward guide for the smoke, and a pocket for the collection of sediment in the boiler, substantially as described.
3. A locomotive having a boiler substantially T-shaped in longitudinal section and 40 the fire-box extending down between and beyond the two sets of the driving-wheels, in combination with a dome at the fire-box end of the boiler, as set forth.
4. The combination, in a locomotive-boiler, 45 of the fire-box extending down between and beyond the two sets of the driving-wheels, the horizontal flues, brace-rods extending through the fire-box, and water-tubes surrounding the same and communicating with the main water-chamber of the boiler, substantially as described.

In testimony that I claim the foregoing as my own I affix my signature in presence of two witnesses.

GUSTAVUS A. KARWIESE.
